RING DISPLAY HOLDER

Jacob Michelson, Brooklyn, N. Y.

Application August 7, 1946, Serial No. 688,991

4 Claims. (Cl. 206—80)

1

2

This invention relates to a ring display holder. Broadly, it is an object of my invention to provide a display holder for finger rings which can hold rings of different widths.

More particularly, it is an object of my invention to provide a ring display holder with recesses to hide the ticket usually attached to the ring and permit a display tag to be visible.

Another object is to provide a ring display holder which can be tilted at different angles and which may be removed from the base if desired.

Still another object is to provide resilient means for holding the rings in a display position.

Another object is to provide an inexpensive ring display holder having a neat and rich appearance.

For a fuller understanding of the nature and objects of my invention, reference is had to the following detailed description in connection with the accompanying drawing, in which:

Figure 1 is a perspective view.

Figure 2 is a sectional view taken through line 2—2 of Figure 1.

Figure 3 is a front view with part of the covering material cut away.

Referring to the drawing, numeral 10 represents a base which may be of wood, plastic, glass, metal or other like materials and may be rectangular, round or other desired shape, and may be covered with velvet 19, or other material. A pair of opposed brackets 11 having indents 12 are embedded within base 10. Brackets 11 are preferably made of flexible metal or plastic.

A block 13, preferably of rectangular shape and made of plastic, metal, wood or the like, is mounted somewhat above the upper surface of base 10 upon brackets 11. Slight indents or depressions are made in the opposed sides of block 13 to receive the indents 12 of brackets 11. The flexibility of brackets 11 holds block 13 and permits it to pivot about the indents 12. Of course, pins and small openings may be substituted for the same purpose.

Block 13 has a recess 14 in the top and a recess 15 in the front central part within which felt padding 16 and 17 respectively is placed. Another recess 18 may be placed in the front to removably hold a ticket stating the price or other information. Block 13 is preferably covered with velvet 19, or other suitable material and is folded back upon itself at the front, as shown at 20, providing a pocket 21 within which a tag 22 usually attached to a ring 23 for display may be hidden. Figure 1 shows the tag 22 slightly above the pocket line; however, pocket 21 may be made deep

enough to hold the usual tag used so that it does not show.

Hinged at the bottom central part of the block 13 is a holding arm 24 made of flexible metal or plastic having a right angle bend at the upper part 25 with an indent 26 which falls within recess 14 when in locked position, felt padding 16 providing resiliency while the flexibility of member 24 holds it in position.

10 In order to display ring 23 upon the holder, arm 24 is opened as shown in the dotted line of Figure 2 and ring 23 is placed over arm 24 and brought down to rest at the lower part of recess 15. Arm 24 is then closed as shown in Figures 1 and 2 clamping the ring against the resiliency of felt padding 17 and the velvet 19. Practically any width of ring can be accommodated and displayed since the ring rests at the bottom of the recess 15. The tag 22 held by string 27 is placed 15 within recess or pocket 21 so that it does not 20 mar the appearance nor does it detract from the appearance of the display.

If the display holder is placed within a low window it may be desirable to pivot block 13 at 25 an angle, or block 13 may be removed from between brackets 11 and placed face upward in horizontal position, if desired.

It is obvious that various changes and modifications may be made in the details of construction and arrangement of parts without departing from the general spirit of the invention.

I claim:

1. A ring display holder of the character described comprising a backing block, a recess in 35 the center of the front of said backing block, a resilient pad within said recess, a hingeable flexible arm pivotally attached to the center of the base of said block for clamping a ring against said block and within said recess and a fabric covering said block, said fabric folded across the front of said block and upon itself creating a pocket for inserting a tag.

2. A ring display holder of the character described comprising a backing block, a recess in 45 the central front of said backing block, a resilient pad within said recess, a hingeable flexible arm at the center base of the front of said block for clamping a ring against said block and within said recess, a fabric covering said block, said fabric folded across the front of said block and upon itself creating a pocket for inserting a tag, and a base having a pair of opposed brackets for pivotally receiving said block and holding said block above said base.

55 3. A ring display holder of the character de-

scribed comprising a backing block, a recess in the central front of said backing block, a resilient pad within said recess, a hingeable flexible arm pivotally attached to the bottom front of said block for clamping a ring against said block and within said recess, a recess in the top of said block for releasably holding said arm, a fabric covering said block, said fabric folded across the front and upon itself creating a pocket for inserting a tag, and a base having a pair of opposed brackets for pivotly receiving said block, said brackets holding said block above said base.

4. A ring display holder of the character described comprising a backing block, a recess approximately in the central front of said backing block, a resilient pad within said recess, a hingeable flexible arm hingeable at the base of the front of said backing block for clamping a ring against said block and within said recess and a fabric covering said block, said recess and said

pad, said fabric folded upon itself across the front of said block creating a pocket for inserting a tag, a recess in the top center of said block for releasably holding said arm, a recess in the central front of said block for holding a display card, and a base having a pair of opposed brackets for pivotly receiving said block and holding said block above said base.
